UNITED STATES PATENT OFFICE.

CURTIS H. DILLON, OF MILAN, MICHIGAN, ASSIGNOR TO DILLON STEAM MOTORS CORPORATION, A CORPORATION OF DELAWARE.

MOTOR.

1,312,523.

Specification of Letters Patent.

Patented Aug. 12, 1919.

Application filed October 28, 1918. Serial No. 260,034.

To all whom it may concern:

Be it known that I, CURTIS H. DILLON, a citizen of the United States, residing at Milan, in the county of Washtenaw and 5 State of Michigan, have invented certain new and useful Improvements in Motors, of which the following is a specification, reference being had to the accompanying drawings.

10 This invention relates to certain improvements in motors, and has relation more particularly to a device of this general character especially designed and adapted for use in connection with an expansion fluid, such as 15 steam, and it is an object of the invention to provide a novel and improved device of this general character comprising a plurality of cylinders, together with associated pistons and crank shaft, and wherein a mechanism 20 is operable from the crank shaft to control the flow of motive fluid to the cylinders in regular succession when the motor is in operation.

It is also an object of the invention to provide 25 a novel and improved motor of this general character comprising a plurality of cylinders or motor units arranged substantially in parallelism and radiating from an associated crank shaft, and wherein the motive fluid is admitted within the cylinders or 30 units in regular succession through similar heads of the cylinders or units.

An additional object of the invention is to provide 35 a motor of this general character comprising a novel and improved valve mechanism, and wherein the induction port of each of the cylinders has coacting therewith a swinging valve which is normally maintained by gravity in closed position and 40 which is thrown into open position through the medium of a rotating cam, and wherein said cam is of duplicate construction and capable of axial movement so that the cam may be adjusted to reverse the operation of 45 the motor or be adjusted to a neutral position to maintain the motor inactive.

The invention consists in the details of construction and in the combination and arrangement of the several parts of my 50 proved motor, whereby certain important advantages are attained and the device rendered simpler, less expensive and otherwise more convenient and advantageous for use, as will be hereinafter more fully set forth.

The novel features of my invention will hereinafter be definitely claimed.

In order that my invention may be the better understood, I will now proceed to describe the same with reference to the accompanying drawings, wherein:

Figure 1 is a view in elevation with portions broken away of a motor constructed in accordance with an embodiment of my invention, the associated pistons and crank being indicated by dotted lines;

Fig. 2 is an enlarged sectional view taken substantially on the line 2—2 of Fig. 1;

Fig. 3 is a fragmentary sectional view taken through the upper portion of my improved motor and substantially on the same line as Fig. 2 with the valve and cam in a second position; and

Fig. 4 is a fragmentary view in top plan of my improved motor with the removable 75 casing omitted and the cam in a neutral position.

As disclosed in the accompanying drawings, C denotes a casing provided with the hangers 1 whereby the same may be suitably 80 supported in desired position. Rotatably supported by the casing is a crank shaft S provided within the casing with the cranks 2, said cranks being successively arranged at relative angles of ninety degrees, as is 85 clearly indicated by dotted lines in Fig. 1.

Supported by the casing C is a plurality of cylinders A, A¹, A², and A³. These cylinders are arranged in parallelism and radial of the crank shaft S. Mounted for rectilinear movement within each of the cylinders is a piston P operatively engaged in a conventional manner with one of the cranks 2 through the medium of a rod 3. M denotes an exhaust manifold common to all 95 of the cylinders and in communication with each of the cylinders through the eduction port 4 produced in a side wall of the cylinder, and immediately above the coacting piston P when said piston is at the limit of its 100 working thrust, as is clearly illustrated in Fig. 2 of the accompanying drawings.

The outer head 5 of each of the cylinders is provided with an induction or admission port 6 arranged substantially at the axial 105 center of the head 5. The port 6 is in communication with a steam chest B common to all of the cylinders A, A¹, A², and A³.

The steam chest B comprises two imposed sections 7 and 8, the section 8 being readily 110

removable so that desired access may be had within the chest as the occasions of practice may require.

The lower or inner section 7 is provided at 5 opposite sides of each of the openings 6 with transversely disposed partitions 9, and between each pair of partitions 9 is positioned a flat valve plate 10 which normally closes the adjacent induction or admission 10 port 6 and which plate assumes its normal position by gravity. The valve 10 has one marginal portion in contact with a side wall of the section 7 and the chest B, and said marginal portion 11 of the valve 10 is bevelled so that said valve 10 may have requisite 15 swinging or rocking movement relative to the coacting port 6. The inner marginal portion of the plate at substantially its longitudinal center is provided with the upper 20 standing arm or post 12 substantially perpendicular to the valve 10, or more particularly the under or working face of said valve.

Disposed through the chest B and longitudinally thereof is a shaft 14 which is supported both for rotary movement and for endwise movement. One end portion of the shaft 14 extends within an outwardly directed guide easing or shell 15 carried by an 25 end of the chest B while the opposite end portion of the shaft 14 extends exteriorly of the chest B at the opposite end thereof. Keyed to the extended portion of the shaft 14 is a gear wheel 16, and said wheel 16 is 30 comprised in a train of gears driven from the crank shaft S. This train of gears is preferably inclosed within a casing 17 so that said gears may run in oil. The connection between the gear 16 and the shaft 14 is 35 such as to cause the same to rotate in unison but permits an endwise movement of the shaft 14 independently of the gear 16 for a purpose to be hereinafter more particularly referred to.

Coacting with each of the valves 10 or 40 more particularly the arm or post 12 thereof is an operating member O, which has its central portion 18 cylindrical and of such diameter as to be free of the arm or post 12 when the member O is in neutral position. The opposite end portions of the member O are provided with the reversely arranged duplicate cams 19 and arranged at 45 opposite sides of a radius.

Each of the cams 19 upon proper adjustment or movement of the shaft 14 is adapted 50 to engage the arm or post 12 of the adjacent valve 10 for lifting the valve 10 at the proper moment for the admission of the motive fluid within a cylinder, and to release 55 said valve 10 to permit the same to return to its normal or closed position after the piston has traveled a partial distance along its working thrust. It is to be noted that 60 the opposed faces 20 of the cams 19 are in-

clined so that when it is desired to start or reverse the motor O will promptly coact with the arm or post 12 upon the requisite endwise movement of the shaft 14 the inclined faces 20 will assure the proper action 70 upon the valve 10 as the occasion may require.

Endwise movement may be imparted to the shaft 14 in any desired manner, but as is illustrated in Fig. 1, a hand lever 21 is operatively engaged with the extended portion of the shaft 14 and said lever 21 is provided with a latch mechanism 22 coacting with a rack 23 suitably supported by the chest B.

24 denotes a conduit in communication 80 with the chest B and leading from a suitable source of fluid supply. It is also to be understood that power may be transmitted from the crank shaft S in any manner or for any purpose desired. In operation, the valves 10 of the cylinders A, A¹, A², and A³, are 85 operated in regular succession. By referring to Fig. 1, the piston P within the cylinder A is at the end of its stroke and the valve 10 coacting with said cylinder has been adjusted into open position for the admission 90 of steam. After the cylinder has traveled a partial distance on its working thrust and before exhaust, the valve 10 is closed. Such position is indicated by dotted lines in cylinder A¹. The expansion of the steam confined within the cylinder results in the piston completing its stroke so that when the piston has assumed the position as indicated by dotted lines in cylinder A² exhaust will 95 occur, and during the working thrusts of the pistons P within the cylinders A² and A³, the piston P within the cylinder A will have been returned to the position indicated by dotted lines. The operation of the pistons P within each of the cylinders is the same as the foregoing, and occurs in regular succession so that the desired rotation of the shaft S for the transmission of power is 100 obtained.

110 From the foregoing description, it is thought to be obvious that a motor constructed in accordance with my invention is particularly well adapted for use by reason of the convenience and facility with which it 115 may be assembled and operated, and it will also be obvious that my invention is susceptible of some change and modification without departing from the principles and spirit thereof, and for this reason I do not wish to 120 be understood as limiting myself to the precise arrangement and formation of the several parts herein shown in carrying out my invention in practice except as hereinafter claimed.

125 I claim:

1. In a motor, the combination of a plurality of cylinders, associated pistons and crank shaft, a steam chest common to all of the cylinders, each of said cylinders being 130

- provided in its outer head with a port in communication with the steam chest, a flat valve plate coacting with each of the cylinders and normally closing the admission port thereof, a marginal portion of the plate being in contact with a side wall of the chest, and timed means for swinging the valve plates in regular succession away from the heads of the cylinders to open the admission ports thereof.
2. In a motor, the combination of a plurality of cylinders, associated pistons and crank shaft, a steam chest common to all of the cylinders, each of said cylinders being provided in its outer head with a port in communication with the steam chest, a flat valve plate coacting with each of the cylinders and normally closing the admission port thereof, a marginal portion of the plate being in contact with a side wall of the chest, timed means for swinging the valve plates in regular succession away from the heads of the cylinders to open the admission ports thereof, said chest being divided by partitions, the valve plates being arranged between adjacent partitions.
3. In a motor, the combination of a plurality of cylinders, associated pistons and crank shaft, a steam chest common to all of the cylinders, each of said cylinders being provided in its outer head with a port in communication with the steam chest, a flat valve plate coacting with each of the cylinders and normally closing the admission port thereof, a marginal portion of the plate being in contact with a side wall of the chest, and timed means for swinging the valve plates in regular succession away from
- the heads of the cylinders to open the admission port thereof, the marginal portion 40 of the valve plate in contact with the side wall of the steam chest being beveled to facilitate its swinging movement away from the cylinder head.
4. In a motor, the combination of a plurality of cylinders, associated pistons and crank shaft, a steam chest common to all of the cylinders, each of said cylinders being provided in its outer head with a port in communication with the steam chest, a flat 50 valve plate coacting with each of the cylinders and normally closing the admission port thereof, a marginal portion of the plate being in contact with a side wall of the chest, timed means for swinging the valve 55 plates in regular succession away from the heads of the cylinders to open the admission ports thereof, said chest being divided by partitions, the valve plates being arranged between adjacent portions, said partitions 60 being of a height less than the height of the chest.
5. In a motor, the combination with a cylinder, an associated piston and crank shaft, the outer head of the cylinder being provided with an admission port, a flat valve plate normally closing said port and rocking on an edge, an outstanding post carried by the valve, and a cam coacting with said post for rocking the valve into open position.

In testimony whereof I hereunto affix my signature in the presence of two witnesses.

CURTIS H. DILLON.
